William G. Bryant,
INVENTOR
BY Victor J. Evans

WITNESS:

William Thompson

ATTORNEY

UNITED STATES PATENT OFFICE

WILLIAM GROVER BRYANT, OF MARION, NORTH CAROLINA

CIGARETTE AND CIGAR LIGHTER

Application filed April 1, 1929. Serial No. 351,801.

The invention relates to a cigarette or cigar holder and more particularly to a cap adapted to cover the exposed end of the holder.

5 The invention is an improvement on the application filed by William G. Bryant August 17, 1927, Serial No. 214,717.

The object of the invention is to provide a cap which will cover, at all times, the 10 exposed end of a cigarette or cigar holder except at the insertion of the cigarette or cigar and will provide a means for smoking the cigar or cigarette without the light from the burning cigarette being visible.

15 A further object of the invention is in providing means for lighting the cigar or cigarette with the cap on the end of the cigarette holder and at the same time preventing any light from emanating from the 20 holder.

A still further object is in providing a removable piece of emery in the cap so that a match may be inserted through one side and ignited on the emery to thereby light 25 the cigar or cigarette.

The invention is illustrated in the accompanying drawings, in which:—

Figure 1 is a longitudinal sectional view of the holder, cigarette and match.

30 Figure 2 is a top plan view.

Figure 3 is a side elevation of the cap.

Figure 4 is a section on the line 4—4 of Figure 3.

Figure 5 is a top plan view of the cap with 35 the emery removed.

Figure 6 is a series of views, showing the emery in bottom plan side and end elevation.

The cigarette holder comprises a body portion 7, having a mouth piece 8 adapted to 40 hold a cigarette 9, all of which is fully explained in the corresponding application, Serial No. 214,717. A cap 10, open at one end, is adapted to fit the end of a cigarette holder, being formed with a shoulder 11, 45 which abuts the end of the body portion 7, a depending part 12 extending down into the bottom of the holder forming a more substantial support. The cap is provided with a plurality of holes 13 to permit air to enter 50 the holder and assist in the combustion of the

cigarette. A rectangular shaped opening 14 is also formed in the cap, the sides of the opening converging so that the opening is smaller at the inner surface than at the outer surface. A block of emery 15, shaped to fit 55 the hole 14, is held in place by a member 16, which is pivotally mounted on the cap at 17. The hole diametrically opposite the opening 14 is made large enough to admit the head of a match as shown at 18. A tapered socket 60 19 is formed in the closed end of the cap and serves the purpose of extinguishing the lighted end of the cigarette which may be pushed forward into the socket. The member 16 is formed with a slight upstanding 65 end 20 which allows easy turning of this member for removal of the emery.

In use, after the cigarette has been inserted, the cap is put on the holder and a match put through the opening opposite the emery. 70 By a slight frictional engagement with the emery either by turning or looping, the match is ignited and the cigarette lit, the match being extinguished on being withdrawn from the cap. This is accomplished by making the 75 opening 18 just large enough to admit the match. The piece of emery can be renewed at any time by simply swinging the member 16 upon its pivot 17, removing the emery from the opening 14 and inserting a new 80 block of emery. This allows the holder to be practically everlasting and provides a simple and efficient means for smoking a cigarette under conditions where the showing 85 of a light would be disadvantageous.

What is claimed is:—

1. A cap for a cigarette holder, adapted to prevent light from emanating from the lighted end of the cigarette, a means carried within the cap and removable from the outside of said cap to provide striking engagement with a match to ignite the cigarette, and pivotally mounted resilient means upon the outside of the cap and detachably engaging the match striking means to hold the latter in place.

2. A cap for cigarette holders having a series of holes, the said cap also having a rectangular opening having converging side walls so that the inner surface of the open-

ing is smaller than the outer surface, a correspondingly shaped block of emery carried in the opening, and a means for retaining the emery in the cap.

- 5 3. A cap having a series of holes, the said cap having a rectangular opening, a block of emery carried in the rectangular opening, a resilient member pivotally carried on the cap adapted to engage the outside surface of
10 the emery and retain the said emery in the cap, one of the holes of the cap diametrically opposite the rectangular opening being formed large enough to admit a match whereby the said match may be ignited by a frictional engagement with the emery, the said emery being removable.

In testimony whereof I affix my signature.
WILLIAM GROVER BRYANT.
